UNITED STATES PATENT OFFICE.

PHILIPP HAKE, OF HOBOKEN, NEW JERSEY.

DESIGN FOR VISITING-CARDS.

Specification forming part of Design No. **11,511**, dated November 18, 1879; application filed October 3, 1879.
[Term of patent 7 years.]

To all whom it may concern:

Be it known that I, PHILIPP HAKE, of Hoboken, in the county of Hudson and State of New Jersey, have invented a new and original Design for a Visiting-Card, of which the following is a specification.

The accompanying drawing represents a face view and an end view of a visiting-card embodying my design.

This invention relates to a new ornamentation of the edges of a visiting-card; and it consists in a new design of the embossing applied to the beveled edges of such a card.

The card A has beveled edges *a* along its entire contour, which edges are, by preference,

gilt or silvered. Diagonal parallel lines are formed, preferably by embossing, on said beveled edges, thereby imparting to them a peculiar appearance, the diagonal lines being depressed stripes or furrows in said beveled edges.

I claim—

The design for the card A, which consists in the diagonal stripes or furrows on the beveled edges of said card, substantially as shown.

PHILIPP HAKE.
